INVENTOR.
FREDRICK J SEVERIN.
BY A.B. BOWMAN
ATTORNEY

UNITED STATES PATENT OFFICE.

FREDRICK J. SEVERIN, OF SAN DIEGO, CALIFORNIA.

APPARATUS TO FACILITATE THE MAKING OF HONEY FRAMES.

Application filed March 8, 1922. Serial No. 542,184.

To all whom it may concern:

Be it known that I, FREDRICK J. SEVERIN, a citizen of the United States, residing at San Diego, in the county of San Diego and State of California, have invented a certain new and useful Apparatus to Facilitate the Making of Honey Frames, of which the following is a specification.

- My invention relates to an apparatus to facilitate the nailing and wiring of honey frames and the objects of my invention are: First, to provide an apparatus of this class which is adapted to receive the machine cut frames and hold the same in place therein and the separate parts with each other for nailing; second, to provide an apparatus of this class which will receive and hold various types of frame parts; third, to provide an apparatus of this class which will receive the nailed frames and grip the end pieces thereof contracting and warping the same to facilitate the wiring of said frame thereby inherently stretching the wires when the frame is released; fourth, to provide novel means for gripping, contracting and warping the end pieces of the honey frame and holding the same in certain position; fifth, to provide an apparatus of this class in combination with a means for making a loop on one end of said wire; sixth, to provide an apparatus of this class which is novelly constructed; seventh, to provide an apparatus of this class which is applicable for cross or parallel wired frames, and eighth, to provide an apparatus of this class which is very simple and economical of construction, durable, portable, easy to adjust and operate, and which will not readily deteriorate or get out of order.
- With these and other objects in view as will appear hereinafter my invention consists of certain novel features of construction, combination and arrangement of parts and portions as will be hereinafter described in detail and particularly set forth in the appended claims reference being had to the accompanying drawings and to the characters of reference thereon which form a part of this application, in which:
- Figure 1 is a front elevational view of my apparatus showing a honey frame of the cross-wired type in clamped position thereon; Fig. 2 is a plan view thereof showing

portions of the honey frame broken away to facilitate the illustration; Fig. 3 is an end view thereof; Fig. 4 is a sectional elevational view through 4—4 of Fig. 1; Fig. 5 is an enlarged fragmentary perspective view of the adjustable members for taking care of the various sized frame parts; Fig. 6 is another enlarged fragmentary perspective view showing means for positioning and holding the frame parts for nailing; Fig. 7 is a front elevational view of a parallel-wired honey frame showing another common method of wiring the honey frame.

Like characters of reference refer to similar parts and portions throughout the several views of the drawings.

The table member 1, upright member 2, braces 3, positioning members 4, spacers 5, angle 6, adjustable guides 7, washers 8, screws 9, clips 10, gripping arms 11, pivot pins 12, lever 13, screw 14, bolt 15, operating arm 16, quadrant 17, support 18 and the crank 19 constitute the principal parts and portions of my structure.

The table member 1 is provided with suitable supports or legs 1^a near its ends so that the operation of the arm 16 may not be hindered by encountering any obstacle under said table member between its ends. Said table member is provided with an upright member 2 near its middle portion and reinforced therewith by the braces 3. The table member 1 is provided with a positioning member 4 adjacent the front side of the upright member 2 mortised in said table member and upright member and secured thereto by means of the screws 4^a. Said member 4 is provided with lugs or stops 4^b at either end for positioning the member A of the honey frame therebetween in its reverse order. A guide portion 4^c is provided at the front side of said positioning member to prevent the member A slipping out of the lugs 4^b. Said positioning member is further provided with spacers 5 secured to the back upright portion of said positioning member for spacing said member A from the back upright portion of said positioning member to facilitate the introduction or the joining of the two members A and B of the honey frame as shown best in Fig. 6 of the drawings. The lugs 4^b are further adapted to prevent the member A being displaced when

joined to the member B by driving in the 5 nails C while the honey frame is in the position as shown in Fig. 6 of the drawings. With the member A positioned downwardly 10 the rail D is nailed to the members B. An angle 6 is provided at the upper portion of the upright member 2 preferably mortised therein and secured thereto by the screw 6^a. The angle 6 is somewhat shorter than the 15 distance between the inside of the upright member B of the honey frame. A clip 10 is provided at either end of the upper leg of the angle 6 to permit ready adjustment of the space between the upright members of said 20 honey frame. Said clip 10 is preferably made of spring material so that it will positively engage said angle and serve as a positive stop. The angle 6 is provided with slots 6^b at either end thereof and adapted 25 to receive the adjustable guide member 7 which holds the upright members B of the honey frame against the clip 10. Said adjustable guide member 7 is provided with the gradually rounded guide portion 7^a to facilitate the introduction of the upright members B between said guide member 7 and said clip 10. Said guide member 7 is further provided with a slot 7^b adapted to receive the screw 9 and at the same time be 30 shiftable thereon. A washer 8 is interposed between the head of the screw 9 and the face of the adjustable guide member 7 and the angle 6 to retain said guide member. Said screw 9 is provided with a nut 9^a to 35 relieve, adjust and clamp said guide member as desired. The grip arms 11, provided with right angled gripping portions 11^a at their extreme ends, are adapted to grip the upright members B of the honey frame. 40 Said grip arms 11 are reciprocably mounted in slots 2^b in the front face of said upright member 2. Said grip arms are pivotally mounted on and secured to the lever 13 by the pins 12. Said lever is also pivotally 45 mounted in a recess 2^a in said upright member 2 on the bolt 14 secured in said member 2. Said lever 13 extends through the table member 1 and is provided in said extended end with a slot 13^a adapted to receive 50 the operating arm 16 therein. The pivot bolt 15 is secured on the under side and back portion of said table member by the nut 15^a screwed thereon. The operating arm 16 is provided at its rear end with a lug 16^a and 55 pivoted on the bolt 15 and secured thereon by the nut 15^b. Said operating arm is adapted to ride on the quadrant 17 and adapted to be received by the notches 17^a therein. A portion of said operating arm 60 extends beyond said quadrant for gripping the same. Said quadrant is secured to the front edge of the table member 1 by the screw 17^b. A recess 2^a is provided in the front face of the upright member 2 at one 65 corner thereof to provide clearance to facili-

tate the gripping of the wire around the hook F¹ in the upright members of said honey frame. A support 18, preferably made out of sheet metal, as shown in Fig. 1 of the drawings, is provided at one end of 70 said table member 1. A slot 2^a is provided in said table member to annex one leg of said support, the other leg being bent around the bottom face of said table member. Thus it may be seen that the member 18 is self supporting and may be removed from said table member as desired. A crank 19 is revolvably mounted in said support and is prevented from becoming free from said support by a loop 19^a bent in 75 said wire between said legs of said support. A handle 19^b is provided at one end of said crank and a hook portion 19^c is provided at its other end so that the light wire which is generally used in wiring honey frames is readily and easily bent around said hook portion and said handle 19^b given a few 80 turns will form a loop at the end of said wire.

The nails F are preferably driven into the 85 upright members B of the honey frame before assembling with the other members A and D. The assembled honey frame is placed in the machine as shown in Fig. 1 of the drawings and the operating arm is 90 shifted to the right thus clamping and securing said frame, at the same time contracting and warping the upright members B thereof. The loop is then twisted on the 95 end of the wire as described above and hooked over the hooks F¹, F², F³, and F⁴ respectively and then back to the hook F¹, 100 twisted, and cut off.

It is obvious that when relieving the 105 strain on the upright members B by shifting the operating arm to the left the wires previously strung become taut.

The upright members B are provided with 110 holes B¹ so that the wire may be strung in said frame as shown in Fig. 7 of the drawings. The adjustable guide member 7 and the gripping arm 11 are so spaced and constructed that they will not interfere with holes B¹ for said other means of wiring.

It is therefore obvious that my apparatus is applicable to either and other methods of wiring the honey frame.

Though I have shown and described a particular construction, combination and arrangement of parts and portions I do not 120 wish to be limited to this particular construction, combination and arrangement but desire to include in the scope of my invention the construction, combination and arrangement substantially as set forth in the 125 appended claims.

Having thus described my invention what I claim as new and desire to secure by Letters Patent is:

1. A honey frame assembling apparatus. 130

- including a table member, an upright member secured at a right angle thereto, a positioning member secured to said table member at the base of said upright member, adjustable guide and retaining means secured at the upper part of the front face of said upright member, and means for simultaneously gripping and contracting both of the normally vertical members of a honey frame supported by said guide and retaining means. 5
2. A honey frame assembling apparatus, including a table member, an upright member secured to the top face of said table member and substantially at a right angle thereto, a positioning member secured to said table and said upright members at the base of the latter, spacers secured to said positioning member, an angle secured to the upper part 10 of the front face of said upright member, clips secured to each end of said angle for spacing the vertical members of honey frames, adjustable guides secured to said angle, gripping arms reciprocably mounted in said upright member for gripping and contracting the vertical members of said honey frames, a lever pivotally secured to said gripping arms and pivotally mounted in said upright member, an operating arm pivotally mounted on the under side of said table member and engaging the extended portion of said lever and a quadrant provided with notches adapted to engage said operating arm. 15
3. A honey frame assembling apparatus, including a table member, an upright member secured to the top face of said table member and substantially at a right angle thereto, a positioning member secured to said table and said upright members at the base of the latter, spacers secured to said positioning member, an angle secured to the upper part 20 of the front face of said upright member, clips secured to each end of said angle for spacing the vertical members of the honey frames, adjustable guides secured to said angle, gripping arms reciprocably mounted in said upright member for gripping and contracting the vertical members of said honey frames, a lever pivotally secured to said gripping arms and pivotally mounted in said upright member, an operating arm pivotally mounted on the under side of said table member and engaging the extended portion of said lever and a quadrant provided with notches adapted to engage said operating arm. 25
4. In an apparatus of the class described, a table member, an upright member secured on the upper side of said table member, a positioning member secured to said table member contiguous to the base of said upright member, retaining means secured at the opposite ends of the upper portion of said upright member on the front face thereof, contracting members pivotally mounted 30 on the front face of said upright member intermediate the top and bottom sides thereof and lever and quadrant means for operating and securing said contracting members in certain positions. 35
5. In an apparatus of the class described, a table member, an upright member secured on the upper side of said table member, a positioning member secured to said table member contiguous to the base of said upright member, retaining means secured at the opposite ends of the upper portion of said upright member on the front face thereof, contracting members pivotally mounted 40 on the front face of said upright member intermediate the top and bottom sides thereof and lever and quadrant means for operating and securing said contracting members in certain positions. 45
6. In an apparatus of the class described, a table member, an upright member secured on the upper side of said table member, a positioning member secured to said table member contiguous to the base of said upright member, retaining means secured at the opposite ends of the upper portion of said upright member on the front face thereof, contracting members pivotally mounted 50 on the front face of said upright member intermediate the top and bottom sides thereof and lever and quadrant means for operating and securing said contracting members in certain positions. 55
7. In an apparatus of the class described, a table member, an upright member secured on the upper side of said table member, a positioning member secured to said table member contiguous to the base of said upright member, retaining means secured at the opposite ends of the upper portion of said upright member on the front face thereof, contracting members pivotally mounted 60 on the front face of said upright member intermediate the top and bottom sides thereof and lever and quadrant means for operating and securing said contracting members in certain positions. 65
8. A honey frame assembling apparatus, including a horizontal member, a vertical member secured thereto and extending longitudinally therewith above the same, positioning members secured to said horizontal member near its opposite ends, positioning members secured to said vertical member near its upper side near its ends and lever operated contracting means positioned intermediate said positioning means on said horizontal member and said upright member. 70
9. A honey frame assembling apparatus, including a horizontal member, a vertical 75 member secured thereto and extending longitudinally therewith above the same, positioning members secured to said horizontal member near its opposite ends, positioning members secured to said vertical member near its upper side near its ends and lever operated contracting means positioned intermediate said positioning means on said horizontal member and said upright member. 80
10. A honey frame assembling apparatus, including a horizontal member, a vertical 85 member secured thereto and extending longitudinally therewith above the same, positioning members secured to said horizontal member near its opposite ends, positioning members secured to said vertical member near its upper side near its ends and lever operated contracting means positioned intermediate said positioning means on said horizontal member and said upright member. 90
11. A honey frame assembling apparatus, including a horizontal member, a vertical 95 member secured thereto and extending longitudinally therewith above the same, positioning members secured to said horizontal member near its opposite ends, positioning members secured to said vertical member near its upper side near its ends and lever operated contracting means positioned intermediate said positioning means on said horizontal member and said upright member. 100
12. A honey frame assembling apparatus, including a horizontal member, a vertical 105 member secured thereto and extending longitudinally therewith above the same, positioning members secured to said horizontal member near its opposite ends, positioning members secured to said vertical member near its upper side near its ends and lever operated contracting means positioned intermediate said positioning means on said horizontal member and said upright member. 110
13. A honey frame assembling apparatus, including a horizontal member, a vertical 115 member secured thereto and extending longitudinally therewith above the same, positioning members secured to said horizontal member near its opposite ends, positioning members secured to said vertical member near its upper side near its ends and lever operated contracting means positioned intermediate said positioning means on said horizontal member and said upright member. 120
14. A honey frame assembling apparatus, including a horizontal member, a vertical 125 member secured thereto and extending longitudinally therewith above the same, positioning members secured to said horizontal member near its opposite ends, positioning members secured to said vertical member near its upper side near its ends and lever operated contracting means positioned intermediate said positioning means on said horizontal member and said upright member. 130

member secured thereto and extending longitudinally therewith above the same, positioning members secured to said horizontal member near its opposite ends, positioning members secured to said vertical member near its upper side near its ends, lever operated contracting means positioned intermediate said positioning means on said

horizontal member and said upright member and means for securing said contracting members in certain contracted positions.

In testimony whereof, I have hereunto set my hand at San Diego, California, this 1st day of March 1922.

FREDRICK J. SEVERIN.
